DRIVE-IN CANOPY

J. D. Lane, 5420 E. Lancaster, Fort Worth, Tex.

Filed Mar. 6, 1959, Ser. No. 54,866

Term of patent 14 years

(Cl. D13—1)

FIG. 4.

FIG. 5.

FIGURE 1 is a perspective view of a drive-in canopy showing my new design a corner portion thereof being broken away for convenience of illustration.

FIGURE 2 is an enlarged broken elevation of the facia of my new design.

FIGURE 3 is a further enlarged horizontal section of the facia illustrated in FIGURES 1 and 2.

FIGURE 4 is a bottom sectional plan view.

FIGURE 5 is an enlarged vertical sectional view taken on line 5—5 of FIGURE 4.

The dominant features of my design reside in the portions shown in full lines.

I claim:

The ornamental design for a drive-in canopy, substantially as shown and described.
